TELEPHONE SUBSET

Ernest S. McLarn, Manhasset, N. Y., assignor to
 International Standard Electric Corporation,
 New York, N. Y., a corporation of Delaware

Application December 24, 1937, Serial No. 181,493

10 Claims. (Cl. 179—100)

This invention relates to telephone subsets and pertains more particularly to hand set mountings or desk sets wherein the various components ordinarily put in the bell box are instead included in the hand set mounting or desk set itself.

It is an object of my invention to provide an improved form of telephone hand set mounting or desk set which is simple in construction, small in size and durable in operation.

A further object of my invention is to provide a telephone hand set mounting or desk set which may be quickly, easily and cheaply repaired when necessary.

In accordance with my invention I provide a hand set mounting or desk set, hereinafter for simplicity referred to as a desk set, wherein the ringer unit, condenser and inductance coil are each individually potted so as to be protected from moisture and all of these elements are positioned within the desk set and connected together in the necessary manner without the aid of connecting cables or exposed wires. This is done by providing a molded terminal block carrying a plurality of terminal connections and imbedded conductors, by means of which the several component parts of the desk set may be interconnected by use of binding screws.

Preferably, this molded terminal block also carries the spring nest of the plunger switch whereby exposed circuit connections are still further reduced.

The above mentioned and further objects and advantages of my invention and the manner of attaining them will be more fully explained in the following description and accompanying drawings.

Fig. 1 is a side elevation view partly in section taken along section line 1—1 of Fig. 2, of a telephone desk set constructed in accordance with my invention.

Fig. 2 is a horizontal sectional view taken along section line 2—2 of Fig. 1.

Fig. 3 is a fragmentary sectional view showing the cradle assembly of Fig. 1 rotated 180° so that the desk set may be attached to the side of a desk or to a wall.

Figs. 4, 5 and 6 are, respectively, plan view, front view and end view of the terminal block forming part of the assembly shown in Fig. 1.

Fig. 7 is a sectional view taken along section line 7—7 of Fig. 4.

Fig. 8 is a sectional view taken along section line 8—8 of Fig. 7.

Fig. 9 is a sectional view taken along sectional line 9—9 of Fig. 4.

Fig. 10 is a view similar to Fig. 9 but showing in addition the clamping means for making the necessary connections.

Fig. 11 is a view similar to the left hand part of Fig. 7 but showing in addition the clamping means for making the necessary connections.

Fig. 12 is a plan view of a metal punching used in making the connections inserted in the terminal block.

Fig. 13 shows in plan view and partly in section an alternative method of making the terminal block.

Fig. 14 shows a sectional view taken along the line 14—14 of Fig. 13.

Fig. 15 shows the circuit connections for the desk set.

Referring more particularly to Fig. 1, reference numeral 1 indicates a base plate having attached thereto, e. g. by spot welding, a bracket 2. This bracket carries at its upper end a closure collar 3, which is spot welded or otherwise fastened to the upper end of the bracket. A cradle assembly 4, is positioned above and supported by the bracket, this assembly comprising a molded or cast cradle 5 having a metal insert 6 in the form of a ring or sleeve which projects through a corresponding opening 7 in the closure collar 3 and bracket 2 and serves as a pivot point or bearing around which the cradle assembly may be rotated through an angle of 180° whereby the cradle assembly may be positioned either at right angles to the base plate, as shown in Fig. 1, or in a direction substantially parallel with the base plate, as shown in fragmentary view 3.

The first position permits the use of the device as a desk set while the latter position permits the use of the device as a wall set attached either to the wall of a room or to the side of a desk. In both positions the hand set which rests on the cradle is readily accessible and the position of the cradle is such as firmly to hold the hand set.

The ring or sleeve 6 has adjacent one end thereof a circular depression 8 in which is resiliently positioned a holding ring or wire 9 which acts to prevent the removal of the cradle assembly from the bracket 2 by which it is supported. Reference numeral 10 indicates a detent or spring pressed plunger which is adapted to fit in one of two depressions 11 and 12 in the face of the cradle 5 which lies adjacent to the closure ring 3. In the position of the parts shown in Fig. 1, the detent 10 presses into the depression 11.

sion 11 holding the cradle in a position at right angles to the base plate. On the other hand, when the cradle is rotated to 180°, as shown in Fig. 3, the detent then engages with depression 12. The detent pin is pressed towards the cradle 5 by means of a leaf spring 13 fixed to the bracket 2.

The cradle 5 has a countersunk opening 14 therein within which is positioned rod 15 of the plunger switch indicated generally by reference numeral 16. This rod passes through a hard rubber bushing 17 and then through a roller bearing guide 18, the latter having two rollers 19 and 20 which serve to take up side thrust of the rod 15. This side thrust results from the contacting of conical head 21 fixed to the rod with actuating contact arm 22 of spring nest 23. This contact arm has a roller 24 journaled thereto, which makes the actual contact with the conical head 21. Twenty-five (25) indicates a spring pressing against a washer 26 which is in turn held in place by presser bar 27 to which the end of rod 15 is screw threaded at 28. A cover 29 fits over the cradle assembly and is fastened to the base at one end by means of a projection 30 on the inside of the cover engaging with a clip 31 attached to the base plate, and at the other end by a screw 32 which engages with a hole in the bracket 2. The closure collar 3 fits within a corresponding opening in the cover 29 and since this ring is preferably formed of resilient and relatively thin metal it conforms to the shape of the opening and forms a complete dust-tight closure. This function is aided by the somewhat flaring 35 shape of the closure collar which insures a wedging action when the cover 29 is placed in position and secured to the base plate. The cover, as shown in Fig. 1, has an instrument blank 33 attached thereto which may be removed for the insertion of a dial.

Attached to the base plate 1 are terminal block 34 and active circuit component units including induction coil 35, ringer 36 and condenser 37. The terminal block 34 is preferably of molded material having imbedded therein the necessary connections which terminate in a series of terminals 38, 39, 40, 41, 42, 43, 44, 45, 46, as shown, for example in Fig. 2. This terminal block is held in position on the base plate by means of screws 47, 48 and 49. The induction coil, ringer and condenser, each have terminals to engage with those of the terminal block just mentioned and are attached thereto by binding screws. The end of each of these units opposite that from which the connections project, is attached to the base plate by means of a screw and clamp as shown at 50, 51 and 52. Each of the several units, just mentioned is preferably positioned within a suitable open sided housing or casing and protected by high melting point potting compound. The housings are desirably of Bakelite or other molded insulating material but alternatively may be of metal, the proper insulating bushings being supplied for the terminals.

Referring to the induction coil and the condenser, the open sides of their casings are preferably placed next to the base plate while the ringer housing is positioned with its open side up, allowing an adjustment of the biasing spring 53 and other parts of the clapper rod and armature assembly 54 may be made.

As shown in Fig. 2, the case 55 of the ringer 36 has a partition 56 which separates the magnet coils 57 from the clapper rod and armature assembly 54, this partition serving to confine the

potting compound to the magnet coils 57 leaving the clapper rod assembly 54 free from the potting compound.

Figs. 4 to 11, inclusive, show the details of construction of the terminal block 34 and make plain the manner of construction thereof.

It will be clear from these drawings that the several terminal connections 38 to 46, inclusive, are molded into the terminal block and that all of these terminals, with the exception of 43, have 10 connections to various other parts likewise molded into the block 34.

The individual springs of spring nest 23 are likewise molded into the block 34 as shown, perhaps most clearly, in Fig. 7. These springs are 15 welded, soldered or otherwise suitably connected with conductors leading to the proper terminals of the terminal block, as shown in Fig. 8.

Reference numerals 58 and 59 indicate connecting prongs or teeth which are intended to 20 pierce the insulation of a conductor or cord which is to be connected to the terminal block. The cord is arranged to be held in position by means of a clamp 60 and screws 61 which draw the clamp towards the associated prongs and at the 25 same time form a circuit connection between conductor rings 72 and 73. This structure is shown in Figs. 10 and 11. A connector of this type is disclosed in my copending application Serial No. 146,539, filed June 5, 1937.

In Fig. 10 the binding screw arrangement of the terminal connections is shown. This consists of a binding screw 62 which passes through an opening in the terminal connection and engages with a perforated strip of metal having 35 two tongues therein and sold for example under the trade name "Speednut." This perforated strip of metal 63 is U-shaped and is in effect folded around the end of the terminal connection, as shown in Fig. 10. Each of the terminal 40 connections has a projecting finger 64 which extends through a corresponding opening in the loop of the elements 63. This finger serves to retain the loop of metal in position and prevents turning thereof during the tightening of the 45 screw.

As shown in Figs. 4, 7 and 8, a threaded stud or nut 65 is welded, soldered or otherwise fastened to one of the connecting strips 66 of the terminal block and this stud extends above the surface of 60 the block so that a binding screw connection may be made thereto. A connecting link 66', which appears in Figs. 1 and 2, is provided so that a connection can be made either from 65 to 43 or from 43 to 45, depending on whether the desk set is 55 to be used with a loop ringing or grounded ringing circuit. An alternative method of effecting a connection between the conductor 66 and one of the terminals 43 and 45 is shown in connection with Figs. 13 and 14, wherein the switch spring 60 connected to conductor 66 by welding, soldering or other suitable means, is bent at right angles as shown at 67, so as to pass below the ends of the other springs forming the spring nest 23 and out of the block to form an external terminal 68 similar to the terminal connections 38 to 46, inclusive. From this terminal a connector link 69 may be extended to the connector 43. In this case the boss 70 for receiving the holding screw 49 is displaced slightly to the left out of 70 line with the spring nest so that the terminal connector 67 will be out of the path of the holding screw.

Fig. 12 shows a layout of the several conductors and terminal connections which are utilized 75

in the terminal block 34. A single strip of metal may be punched in a single operation to form the several connections shown in Fig. 12, all of these connections except that forming conductor 66 being held together by a single connector strip 71. After the punching operation is completed the prongs 58 and 59 are bent down at right angles. The conductor rings 72 and 73 and prongs are twisted into alignment so as to occupy the position shown in Figs. 7 and 8, then the entire group of conductors with their integrally formed terminal connectors are placed in a mold and insulating material such as Bakelite, hard rubber or the like, is molded around them to form the finished product. After the molding operation is completed the holding strip 71 is sheared off leaving the terminals all in their proper positions ready for electrical connection to form the desired circuit. The stud 65 if used is previously welded to an enlarged portion 74 of the conductor 66 and likewise the springs of the spring nest 23 are welded to the ends 75 of the associated conductors so that when the molding operation is completed the stud 65 is imbedded in the insulation with just its surface showing and likewise the ends of the spring nest are imbedded in the insulation so that they will be held in the proper relative position after the insulation solidifies.

It is possible to cut out all of the parts forming the several conductors in one punching operation because of the arrangement of the apparatus elements which have been selected. By this arrangement of elements which is shown, for example, in Fig. 2 and has been described hereinabove, all cross-over connections which would prevent the punching of all of the conductors in one operation have been avoided and this results from the fact that the condenser and induction coil have been placed on each side of the ringer, as already explained hereinbefore, and furthermore that the hand set cord and line cord have been positioned as shown, the hand set cord being adjacent to the induction coil and the line adjacent to the condenser. Since cross-over connections have been avoided, the assembling and molding operation, as well as the punching operation for forming the conductors, is relatively simple.

Fig. 15 shows a circuit diagram of the desk set, the cases of the several component parts being shown in dotted lines in the interests of clarity. This circuit diagram illustrates the connections using a hand set with the calling dial attached thereto, as shown for example in my copending application Ser. No. 146,539, filed June 5, 1937.

In this drawing reference numerals 16, 77 and 78, indicate respectively, the receiver, transmitter and calling dial, while 79 is the usual terminal block. Eighty (80) is the line cord and 81 the hand set cord. Where the instrument is to be used for the first party of a selective two-party line cooperating with the usual circuits of the rotary system, the link 66 should extend from terminal 43 to 45, while for the second party there should be in addition a strap connection between terminals 44 and 42. Reference numerals 82, 83, indicate louvers or openings in the cover 29 through which the sound of the ringer bells may easily pass.

From the foregoing description it will be seen that I have provided a very simple form of desk set wherein each of the individual parts is separately potted in such manner as to form a moisture and corrosion proof entity, which can read-

ily be inserted into the desk set and removed therefrom as a unit. Furthermore it will be understood that the several units can be associated with the terminal block which carries all of the necessary connections in a very simple, easy and reliable manner, merely by the aid of a screw driver. The terminal block itself, as already stated, carries all of the necessary connections and is firmly fixed to the base plate. The induction coil, ringer and condenser are held firmly in position by screw terminals attaching the same to the terminal block at one end and by means of separate clamping elements at the other end. Therefore, in servicing a desk set of this character in the field, it is necessary merely to locate the defective element or unit, then to remove this by loosening the several screws involved, so that a new unit may be quickly inserted by the use of a screw driver solely and without the necessity for soldering connections. Since the cable and flexible wire connectors ordinarily utilized in conjunction with soldered joints to form the circuit connections of a desk set according to the prior art are eliminated, not only is it assured that circuit difficulties arising from breaking of the several strands of the cable or failure of the soldered joints are obviated, but also the changing of the several units in the desk set is greatly simplified.

Furthermore, since the spring nest 23 is molded into position in the terminal block 34, no looseness of the spring nest in operation can result.

The mounting of the individual units on the base plate and the provision of the bracket 2 for holding the cradle assembly 4, also has the advantage of necessitating only a very simple and cheap cover or housing 29 which is inexpensive to form, for example by a molding operation, since there are no bosses, projections or inserts which would add to the expense of manufacture. The manner of attachment of this cover assures that very quick and easy inspection of the parts of the apparatus may be made merely by removing this cover while the desk set is in this normal position. It is not necessary to turn the desk set upside down and therefore if this instrument is attached to a supporting surface, for example clamped to the side of a desk or to a wall, it is not essential to unclamp the instrument from its support but merely necessary to remove by unscrewing the single holding screw 32. Further, the desk set is a complete operating unit without the cover, facilitating inspection and test. Also because of the spacings of the several terminal connections, which may be different for each active circuit unit, and the relative location of the terminal connections for the units it is impossible to connect the units incorrectly. The easy and accurate connection of the units may be further aided by providing only enough space for the correct positioning of the units, with respect to their corresponding terminal connections, as shown. Thus need for expert technical knowledge in connecting the parts of the telephone set is avoided.

While I have described a particular embodiment of my invention for the purposes of illustration, it should be understood that various modifications and adaptations thereof may be made within the spirit of the invention as set forth in the appended claims.

I claim:

1. A telephone subset comprising a terminal block carrying a plurality of terminal connections, a plurality of individual subset components

having terminals projecting from one end thereof, a base plate for supporting said block and said components, means for securing said terminal block to said base plate, means for joining 5 said terminals of said components directly to said terminal connections, and means for securing said components to said base plate at points spaced from said terminals.

2. A terminal block for a telephone subset 10 comprising a relatively long and narrow mass of insulating material having imbedded therein a plurality of terminal connections, the ends of a plurality of switch springs, and means for interconnecting said terminal connections and said 15 switch springs.

3. A terminal block in accordance with claim 2 wherein is also provided a plurality of connecting prongs for the attachment of external cord connections, means for clamping said cord 20 against said prongs and means for interconnecting said prongs with said terminal connections and said switch springs.

4. A terminal block comprising a plurality of terminal connections, a spring nest, connections 25 between said spring nest and said terminals, said block being of molded material and the ends of said terminal connections and the ends of said spring nest being imbedded therein and interconnected.

30 5. A telephone subset comprising a supporting structure, a terminal block of molded material separate therefrom, fastened thereto and having therein a plurality of conductors ending in integral terminal connections, said terminal connections 35 only extending beyond the dimensions of said block, a plurality of active circuit units having terminals projecting therefrom and means for directly interconnecting the terminal connections

of said block with the terminal connections of said units whereby the length of exposed circuit conductors is minimized.

6. A telephone subset in accordance with claim 5 wherein each of said units is provided with 5 external terminals which have a given spacing corresponding with the spacing of cooperating terminal connections in said connection block.

7. A telephone subset in accordance with claim 5 wherein a spring nest is molded directly in said 10 terminal block and said subset has a plunger rod arranged to operate said spring nest.

8. A telephone subset in accordance with claim 5 wherein the internal connections in said terminal block are so arranged as to eliminate cross- 15 overs inside thereof.

9. A terminal connector block comprising molded insulating material having a plurality of conductors positioned therein, external connections for certain of said conductors, connector 20 prongs for certain of said conductors, screws passing through certain of said conductors and having a conductor clamp associated therewith, said conductor clamp serving in conjunction with said screws to force a conductor cord against said 25 prongs to form a connection and said conductor clamp likewise serving to form a circuit connection between certain of said conductors.

10. A telephone subset comprising a base plate, a bracket secured to said base plate, a cradle 30 assembly carried by said bracket, a cover fitting around said cradle assembly and secured to said base plate, and a flexible collar attached to said bracket around said assembly and in contact with said cover whereby a tight closure is formed between said cover and said assembly. 35

ERNEST S. McLARN.
